Inventor;

John S. Loomis

United States Patent Office.

JOHN S. LOOMIS, OF BROOKLYN, NEW YORK.

Letters Patent No. 78,215, dated May 26, 1868.

IMPROVEMENT IN MACHINES FOR POLISHING WOOD.

The Schedule referred to in these Letters Patent and making part of the same.

TO ALL WHOM IT MAY CONCERN:

Be it known that I, JOHN S. LOOMIS, of the city of Brooklyn, in the county of Kings, and State of New York, have invented a certain new and useful Machine for Sand-Papering and Polishing Wooden or other Mouldings; and I hereby declare the following to be a full, clear, and exact description thereof, reference being had to the accompanying drawings, which are lettered to correspond with and form a part of the specification.

To enable the public to understand the nature of my invention, and those who are skilled in the useful mechanic arts to construct and operate the same, I will describe it as follows, to wit:

Figure 1 is a perspective drawing of my apparatus for sand-papering or polishing wooden or other mouldings.

A is a horizontal movable bed, which is operated backwards and forwards by a crank upon the shaft S, or otherwise.

B is a spring-block, the under side of which is fashioned to receive and correspond with the moulding M, and is provided with a sand-paper surface, next the moulding, or may be used without the paper by simply employing a feeder or sand-cup, D', which distributes the sand, through the pipe T, upon the moulding to be rubbed with block B, which is operated by the reciprocating bed A by means of the arm u.

C is the revolving polishing-brush chamber, and is provided with an emery or sand-box, D, which supplies the brushes W W with polishing-material in a small uniform quantity, distributed through the funnel-shaped tube by the jar of the machine. These revolving brushes, W W, are kept up at a high speed by the rapid revolutions of the transverse shaft o. The brush N is moved horizontally upon the moulding M by the reciprocating bed A, and the mouldings M are fed through the machine upon the adjustable bed G, by the flexible wheels E E, which are also adjusted by any well-known device to suit the different thickness of mouldings; and the block B and stationary block F may be changed to correspond with the different-shaped mouldings upon the bed G, which may be arranged upon springs to produce an upward pressure of the moulding M, in lieu of having the block B hung upon and operated by a spring, as shown in the accompanying drawings.

The above-described machine may be operated by the band-wheels 1 2 3 4 5, or by any other well-known mechanical means.

By the above arrangement I am enabled to perform the work of ten men per day, in a more workmanlike manner, by the employment of two small boys, one to feed the machine, and the other to remove the finished mouldings. Therefore,

What I claim as new and useful, and desire to secure by Letters Patent of the United States, is—

The sand-block or rubber B, cup D', pipe T, revolving brushes W W, dusting-brush N, stationary rubber F, emery-cup D, and adjustable bed G, all combined and operating in the manner and for the purpose substantially as described.

In testimony whereof, I hereunto subscribe my name, in the presence of two witnesses.

JOHN S. LOOMIS.
